LIGHT SENSITIVE LINE TRACING APPARATUS
 Frans Brouwer, Glencoe, Ill., assignor to Stewart-Warner
 Corporation, Chicago, Ill., a corporation of Virginia
 Filed Sept. 19, 1960, Ser. No. 56,920
 20 Claims. (Cl. 250—202)

This invention relates to line sensing devices such as are useful in apparatus to control the patterns of torch cutters, wood sawing machines, clothes cutters, welding tools, milling machines and the like. More particularly, this invention relates to guidance elements and systems using photosensitive means of the general character shown and described in U.S. Patent 2,489,305 to Miles A. McLellan, filed February 12, 1948, and issued November 29, 1949.

It is an object of this invention to provide a sensing element with a variable electric signal output dependent on the position of a sensed line.

It is also an object of this invention to provide a line sensing element which has a simplified construction and has a minimum of moving parts making it economical to construct and to maintain.

Another object of this invention is to provide a sensing element which is less sensitive to changes in the intensity of light impinging on the pattern to be traced.

It is another object of this invention to provide apparatus for guiding heavy or light machinery in accordance with a desired pattern drawn on a movable or stationary sheet of paper or the like.

It is also an object of this invention to provide a system for producing signals which may be used to energize a servo drive mechanism capable of guiding the apparatus and its corresponding operated mechanisms in accordance with a desired complex pattern line even though the line may close upon itself.

Other objects and advantages will be obvious to one skilled in the art with a further reading of this specification. These objects are accomplished in an apparatus embodying the present invention which comprises photosensitive means responsive to variations in light intensity for causing fluctuations in an electric current proportional to the variations in light intensity upon which an image of the optical field including the line is projected. Opaque means are provided for periodically obstructing the image of the field on the current fluctuating means for a portion of a cycle of oscillation. Further means are provided which are responsive to the fluctuations in the electric current to maintain the photosensitive means at a reference position with respect to the line to be traced.

This invention will be better understood upon a further reading of the specification with reference to the attached drawings in which:

FIGURE 1 is an elevation view of a guidance system embodying this invention;

FIGURE 2 is a vertical section view of a sensing head for the guidance system of FIGURE 1;

FIGURE 3 is a bottom view of the photocell and vibrator assembly shown in FIGURE 4;

FIGURE 4 is a vertical section of the photocell and vibrator assembly taken along line 4—4 of FIGURE 3;

FIGURE 5 is an enlarged detail view in perspective of the vibrator assembly;

FIGURE 6 is an enlarged fragmentary view in perspective of the adapter of the assembly shown in FIGURE 4;

FIGURE 8 is a graph showing the vibrator displacement and voltage outputs of the photocell with respect to time, for one embodiment of the invention;

FIGURE 8a is a schematic drawing showing the geo-

2

metric conditions for which the curves of FIGURE 8 are representative;

FIGURE 9 is a graph showing the vibrator displacement and the voltage output of the photocell with respect to time, for another embodiment of the invention;

FIGURE 9a is a schematic drawing showing the geometric conditions for which the curves of FIGURE 9 are representative; and

FIGURE 10 is a schematic representation of the oscillations of the opaque shade with respect to the photocell which represents another embodiment of this invention.

For a description of one embodiment of the invention, reference is made to FIGURE 1 which shows a guidance system 20 comprising a sensing head 22 rotatably mounted in a frame 24. The sensing head 22 is caused to rotate by a 2-phase servo steering motor 26 fixedly mounted on the frame 24 and having a pinion gear 28 engaging a drive gear 30 on the sensing head 22. The steering motor operates by an electric signal which varies in electrical properties in accordance with the position of the sensing head over a line 31. A tachometer generator 33 is directly coupled to the servo steering motor and serves a purpose which will be hereinafter described. The steering motor 26 also rotates a drive mechanism 32 which is rotatably mounted on the frame 24 by means of a gear 34 in engagement with the pinion 28. The driving mechanism 32 has a wheel 36 which is driven by a separate constant speed motor (not shown) within the drive mechanism. The wheel 36 is in friction engagement with the surface upon which is drawn the line 31 and serves to move the whole system 20 in accordance with the signals of the sensing head 22. The guidance system 20 is fixedly connected to a work tool, such as a cutting torch 37, by means of an arm 38 attached to the frame 24. The torch 37 will, therefore, be caused to trace the same pattern the guidance system is following to cut the desired shaped line in work piece 39.

The sensing head 22, which produces the fluctuations in the electric current, comprises, as shown in FIGURE 2, a tubular housing 40 attached to the frame 24 which has an aperture 42 therein abutting a shoulder 44 formed in the housing and secured thereto by appropriate screws (not shown).

A tube 48 is journaled within ball bearings 50 in the interior of housing 40. The bearings 50 are secured by clip rings 52 within annular grooves 54 in the bearings adjacent the ends of the housing 40. The gear 30, which is driven by the pinion 28, encircles the upper end of the tube 48 and is secured thereto by convenient means such as set screw 58.

At the lower end of the tube 48 is positioned a lens assembly 60 which comprises a lens 62 firmly fixed within a lens support 64. The lens assembly 60 is attached to a flange 66 at the lower end of the tube 48 by screws 68 extending through elongated apertures 70 in the lens support and threadedly engage the flange 66. A small plate 72 which is fastened to a flattened portion 74 on the periphery of flange 66 has an adjusting screw 76 passing therethrough and engaging internal threads 78 in the lens support 64 providing for radial adjustment of the lens 62 with respect to the longitudinal axis of the tube 48.

A light source 80 is positioned at the lower end of the sensing element head 22 and is fastened to a collar 82 by a plurality of screws 84. The collar 82 has a flange 86 engaged by the bolts 46 which secure it and the light source to the bottom end of the housing 40. The light source 80 comprises a substantially conical shaped hollow member 88 having a plurality of wells 90 circumferentially spaced around the upper portion 92 of the conical member 88 within which are disposed electric lamps 94. An equal plurality of passages 96 extend from the lower end of the conical member 88 and are

aligned between the lamps 94 and a focal point on the line 31 to be traced.

At the upper end of the sensing head is an assembly 100 comprising a photocell 102, a vibrator assembly 104, and a slip ring and electromagnet subassembly 106, all supported on an adapter 108 fastened to gear 30 by screws 110 extending through a flange 112 on the adapter. It will be noted that the assembly 100 is easily removable from the rest of the sensing head making it readily accessible for maintenance purposes.

The slip ring subassembly 106 comprises a cup-shaped member 116, fabricated of an insulating material, to which are attached four slip ring commutators 118. The slip ring subassembly is secured to a tubular portion 120 of the adapter 108 by screws 122 or other suitable fastening means. The photocell 102 is rigidly secured within an aperture in a bar 124 (FIG. 4) disposed within a groove 126 extending diametrically across the bottom of adapter 108. The bar 124 is secured to the adapter 108 by means of screws 125 passing through enlarged apertures 129 in the bar and threadedly engaging the adapter. It will be seen in FIGURE 3 that the photocell 102 has a substantially rectangular sensitive area 127 which is aligned lengthwise with the longitudinal axis of the bar 124. Wires 132 connect the photocell to slip rings 118a and 118b which are connected by brushes to a circuit to be hereinafter described. The lens 62 near the bottom end of the sensing head 22 is adapted to cast an image of the scanning field 128 (FIG. 2) containing the line 31 on the sensitive area 127 of the photocell 102. The lens is adjusted to view a segment of the line which is displaced a short distance from the axis of rotation of the sensing head. This gives the device its steering sense whereby the steering motor rotates the driving mechanism and the sensing head about their axis pursuant to a sensed transverse deviation of the image of the line from a reference position. It is to be understood that a lens may not be necessary in the sensing head if the photocell is positioned close enough to the line on the work surface. In this case the photocell would be offset from the axis of rotation to give the device its steering sense. An annular light baffle 130 is provided within the tube 48 to prevent unwanted light reflections from reaching the photocell.

The vibrator subassembly 104 comprises an arm 134 having a right angle projection 136 (FIG. 2) forming an opaque shade adjacent to the sensitive area 127 on the photocell 102 between it and the lens 62. The opaque shade extends in a direction across the short dimension of the rectangular sensitive area 127 (FIG. 3). The arm 134 has a U-shaped fold 140 (FIG. 5) at its other end in the same plane as the opaque shade 136. There is a slot 142 (FIG. 4) in the folded end of the arm which extends from the base 144 through a portion of each of the legs 146 of the U-shaped fold. A flat spring 148 is inserted in the slot 142 forming an aperture 150 with the base and two legs of the U-shaped fold. A U-shaped permanent magnet 152 has its base 154 disposed within said aperture 150 and has its legs 155 extending in a direction opposite from the opaque shade end of the arm 134. The arm 134, flat spring 148 and magnet 152 are suitably secured together to form a rigid assembly by means of an epoxy resin or other suitable fastening means.

The ends 156 of flat springs 148 are received in diametrically opposed slots 158 (FIG. 6) at the upper end of the tubular portion 120 of adapter 108. There is a second pair of slots 160 immediately adjacent the spring containing slots 168 forming a tongue 162 therebetween. A wedge (not shown) is driven into each of the slots 160 forcing the tongues 162 against the spring ends 156 securing them in rigid engagement within the slots 158. Thus the arm 134 may be caused to angularly vibrate about an axis described by the center of the flat spring 148 to cause the opaque shade 136 to periodically trav-

erse the image of the scanning field projected on the sensitive area 127 of the photocell 102.

To vibrate the arm 134 the permanent magnet 152 is subjected to a fluctuating magnetic field established by an electromagnet 164 (FIGS. 2 and 4) which is connected to an alternating current source through wires 165, and slip rings 118c and d. The electromagnet 164 has an E-shaped core 166 having legs 167a and b extending towards the legs 155 of the U-shaped permanent magnet 152. A coil 168 is wound around the center leg 167a of the core 166 which causes a fluctuating magnetic field to be established through the outer legs 167b causing the permanent magnet 152, and hence the arm 134, to vibrate in accordance with the oscillations of the energizing current. The electromagnet is implanted in an epoxy resin 169 or the like within the cup-shaped member 116 to hold it firmly therein.

The vibrating assembly is adjusted so that the shade 136 on the arm 134 vibrates with an equal amplitude on either side of a plane which is perpendicular to the sensitive area and includes the center of the scanning field 128. The arm vibrates essentially within a plane which is parallel to the longer dimension of the sensitive area. It will be noted in this particular embodiment that the axis of rotation of the opaque shade is parallel to the plane of the sensitive area. Other configurations are possible, however, as will be described hereinafter.

The opaque shade will align itself generally with the image of the line 31 being traced. The variations in the position of the line with respect to the center of vibration causes changes in the electrical signal output of the photocell which directs the steering motor to turn the sensing head toward the line as hereinafter described. The enlarged holes 129 in the bar 124 permit adjustment of the position of the photocell with respect to the vibrating arm to compensate for any irregularities in the photocell to obtain a properly balanced signal.

The photocell 102 may be of any well known type with appropriate circuitry. FIGURE 7 shows a circuit usable with a photoresistive-type cell whose resistance varies inversely with light intensity on its sensitive area. The photocell 102 is connected in series with a resistor 170 across a negative D.C. voltage. The resistor 172 shown in phantom is not actually included in the circuit but is shown to help describe a certain effect as will be hereinafter described. The vibrator subassembly 104 is schematically shown with the shutter 136 operable to vibrate over the sensitive area 127 of the photocell 102 in response to an alternating current signal applied through transformer 174. A phase adjusting circuit 175 is included in the circuit energizing the vibrator subassembly to compensate for phase shifts in various parts of the electrical circuit. The phase adjusting circuit is not shown in detail as it may be any well known type and does not form a part of this invention.

FIGURE 8 shows an example of the kind of signals that may be derived from the output of the photocell connected in a circuit as shown in FIGURE 7. The curves represent voltage signals at the point 178 at the output of the photocell. In this case it is assumed that the width of the projected line 31 is approximately equal to the width of the shade 136 and that the width of the sensitive area 127 of the photocell 102 is larger than three times the width of the shade 136 as shown in FIGURE 8a. The width of vibration is somewhat but not much smaller than the longitudinal dimension of the sensitive area 127. The top curve a in FIGURE 8 shows the shutter amplitude versus time and the relationship is sinusoidal. Curves b, c, d and e are voltage versus time representations. Curve b shows the signal on the cell 102 when the projection of the line 31 is central which coincides with the shade 136 in the condition when the vibrator is not operating. Curves c, d and e show the signals when the line projection 31 is off center by respectively

$\frac{1}{4}$, $\frac{1}{2}$ and 1 width of the shade 136, as seen in FIGURE 8a.

These graphs may readily be derived by considering the geometry of this example. For example, in curve *b* of FIGURE 8 representing the case where the line 31 is located centrally beneath the sensitive area 127, the light intensity impinging on the sensitive area 127 will be greatest when the shade 136 is also centrally located beneath sensitive area 127. The resistance of the photocell 102 will have its smallest value and the voltage at point 128 will swing towards the ground potential. As the shade 136 moves away from the centermost position, it blocks out an increased portion of the light impinging on the area 127 causing the resistance of photocell 102 to increase, and, hence, cause the voltage at point 178 to swing more negative.

If the frequency of vibration is *f*, we see that the fundamental component in signal *b* is $2f$. However, curves *c*, *d* and *e* exhibit increasing content of the original frequency *f*. This component is in phase with the vibration frequency when the deviation of the projection from the center is in the direction shown in FIGURE 8a and in the opposite phase when the deviation is on the opposite side of the center. When the line is absent, no signal appears at the output of the photocell because the light intensity appearing on the sensitive area is constant.

Hence, from the photocell signals we may derive information on which side and how much off center the deviation is by observing the phase and magnitude of the frequency *f* signal. In addition, the presence or absence of a signal indicates whether the photocell is above a line or not.

FIGURE 9 shows an example of a different configuration in which the width of the sensitive area 127 of the photocell 102 is approximately equal to the width of the projected line 31 and the shade 136 as shown in FIGURE 9a. The curve *a* in FIGURE 9 again represents the shutter amplitude versus time and the curves *b*, *c* and *d* represent the same respective deviations as the like lettered curves in FIGURE 8. It should be noted that the indications of the above example are changed in meaning in this case. That is, absence of any signal now indicates that the system is on the line. The presence of the $2f$ component at its fullest magnitude indicates that there is no line in the scanning field.

The fluctuations in the output of the photocell may be passed through an electric circuit and the information derived therefrom made to control the steering motor to make the photocell follow the line.

With reference again to FIGURE 7, the output of the photocell 102 is fed through two series connected A.C. amplifiers 180 and 182, respectively, to a second harmonic rejector circuit 184, which may take the form of a series resonant circuit to shunt the second harmonic component of the signal to ground. The remainder of the signal is amplified by amplifier 186 and applied to one winding 188 of the two-phase steering motor 26. The other winding 190 of the motor 26 is connected to the same A.C. source energizing vibrator 104 through a capacitor 192. The capacitor provides a 90° phase shift required to properly phase the signals in the windings of the two-phase type motor. The application of a signal corresponding to the phase represented in FIGURE 8 will cause the motor 26 to rotate in one direction and a signal of opposite phase will cause the motor to rotate in the opposite direction. When the photocell is directly over the line, there is essentially no phase shift as the output therefrom is virtually made up of even harmonics of the vibration frequency and thus causes no rotation of the motor.

The tachometer generator 34 is directly connected to the shaft of the motor 26 and has one winding 200 connected to the A.C. source. The other winding 202 is connected to the input of amplifier 186 and provides a signal thereto corresponding to the speed of rotation of the mo-

tor 26. This signal is in opposition to the input from the preceding circuit leading from the photocell 102. When there is a large deviation of the line 31 from the center of the sensitive area 127, a large output results from the photocell and the amplifiers tend to produce a large output to drive the steering motor at a high speed. However, as the velocity of the motor 26 increases the output from the tachometer generator 34 increases and opposes the signal from the photocell thus reducing the output from the amplifier 186. This effect permits the use of large amplification in the servo loop and reduces overshoot since the maximum amplification of the loop only becomes effective when the speed of the steering motor is near 0.

An alarm circuit 204 is connected to the output of amplifier 180 and provides a warning when there is no line in the scanning field image projected on the photocell. It also turns off the A.C. power to the feed motor 205 which drives the wheel 36 in the driving mechanism 32. The alternating current signal from the amplifier 180 is converted to direct current by a conventional rectifier 206 whose output is connected through amplifier 208 to the energizing coil 210 of relay 212. The coil 210, when energized, operates the contacts 194 and 196. The contacts 194 in series with the feed motor are normally open. Contacts 196, which are serially connected with lamp 198 across the A.C. feed source, are normally closed. Thus, when the photocell is over a line a signal appears at the output of amplifier 180 which is rectified and amplified to energize the coil 210 of relay 212 causing normally open contacts 194 to close and normally closed contacts 196 to open. The feed motor is therefore connected directly to the A.C. source and the circuit to the lamp 198 is opened. When, however, the apparatus encounters a discontinuity in the line, there will be no signal at the output of amplifier 180, and the relay 212 will deenergize. Contacts 194, therefore, open to disconnect the feed motor from the A.C. source, and contacts 196 to close to connect the lamp 198 across the A.C. source to warn the operator that the photocell is no longer receiving an image of a line.

The particular warning circuit 204 shown in FIGURE 7 presumes, of course, a configuration of the photocell and vibrator shown and described in FIGURES 8 and 8a. If the configuration of FIGURES 9 and 9a is used, the alarm circuit must be modified to cause the power to the motor to be cut off and the warning light energized when the signal comprises a maximum $2f$ component. When there is no second harmonic component at the output of the amplifier 180 it is indicative that the photocell is over a line, power must be on with the warning light shut off.

It is to be understood that many other modifications may be made to the particular embodiment hereinbefore described. For example, the vibrator assembly might be of a type, as shown in FIGURE 10, in which the opaque shade 136 angularly vibrates about an axis 220 which is perpendicular to the plane of the sensitive area 127 of the photocell, and with equal amplitude on either side of a plane perpendicular to the plane of the sensitive area and intersecting the center of the scanned field. As long as the vibrations are of equal amplitude on either side of the center plane, the angular vibration has no adverse effect on the signal produced by the photocell as it encounters the line.

It has also been found that the operation of the device may be improved when the scanning head is provided with a photocell having a relatively long photosensitive area compared to the peak to peak amplitude of the opaque shade vibrations. A relatively large area of the photocell will then be illuminated without interruption. This area of the photocell does not contribute to the signal but forms a resistive load on the circuit which may be thought of as a variable resistance in parallel with the photocell 102. The resistor 172, shown in phantom in FIGURE 5, represents this resistive load. When the

light level of the image is reduced, the sensitivity of the photocell naturally drops. However, the effective shunting resistance, represented as resistance 172, loading the circuit is increased so that it counteracts the reduction in sensitivity. It has been found that the sensitivity of a photo element having a relatively wide sensitive area is almost independent of small variation of the voltage of the light source.

It is to be understood that the sensing head hereinbefore described is not limited to use with line tracing systems but may be used in many other applications wherein it is necessary to determine the position of a line. For instance, it may be useful as a position determining element in precision gauging equipment such as line standard comparators. It could also be adapted for use as a sensing element in wire gauging instruments or for remote observation of the relative position of machine tool elements with respect to a measuring scale. It is, therefore, intended that the invention should not be limited to the embodiments hereinbefore disclosed, but should embrace all of the embodiments which may be included within the framework of the appended claims.

What is claimed is:

1. A head for a system for scanning a line comprising photosensitive means having a sensitive area positioned to have an image of the scanning field containing the line cast thereon, the length of the sensitive area in a direction transverse to the line being equal to or greater than the width of the image of the line, continuous opaque means disposed between the sensitive area and the line, and means for oscillating said opaque means essentially transversely to the line for periodically obstructing the image of the line on the sensitive area, said opaque means oscillating with equal amplitude across a plane perpendicular to the sensitive area and containing the center of the scanning field.

2. A head for a system for scanning a line comprising photosensitive means having an elongated sensitive area positioned to have an image of the line cast on said sensitive area transverse to the area's longest dimension, totally opaque means disposed between said sensitive area and the line, and means for angularly oscillating said opaque means transversely to the line for periodically obstructing the image on the photosensitive means, the axis of the angular oscillation being positioned within a plane perpendicular to and intersecting said sensitive area.

3. The head of claim 2 wherein the axis of angular oscillation is also parallel to the plane of said sensitive area.

4. The head of claim 2 wherein the axis of angular oscillation is also perpendicular to the plane of said sensitive area.

5. The head as claimed in claim 2 wherein the longest dimension of said elongated sensitive area is approximately equal to or greater than the width of the image of the line.

6. A scanning head for a system for tracing a line comprising a photocell having an elongated rectangular sensitive area, said photocell positioned to have an image of the scanning field containing said line cast upon said sensitive area, an arm having a continuous opaque portion positioned between said sensitive area and the scanning field and extending transversely across said rectangular sensitive area, said opaque portion having a width approximately equal to the image of the scanned line, and means for vibrating said arm to cause said opaque portion to oscillate in a direction along the longer dimension of the rectangular sensitive area.

7. A head as claimed in claim 6 wherein said opaque portion angularly oscillates about an axis positioned in a plane perpendicular to and intersecting the plane of said sensitive area.

8. A head as claimed in claim 7 wherein said axis is also parallel to said sensitive area.

9. A head as claimed in claim 7 wherein said axis is also perpendicular to said sensitive area.

10. The head as claimed in claim 6 wherein the longest dimension of said rectangular field is approximately equal to or greater than the width of the image of the line.

11. A system for scanning a line comprising a scanning head, said scanning head comprising photosensitive means having a sensitive area positioned to have an image of the scanning field containing the line cast thereon, said photosensitive means adapted to cause fluctuations in an electric signal proportional to variations in light intensity, the length of the sensitive area in a direction transverse to the line being substantially greater than the width of the image of the line, opaque means disposed between the sensitive area and the line, means for oscillating said opaque means essentially transversely to the line for periodically obstructing the image of the line on the sensitive area, said opaque means oscillating with equal amplitude across a plane perpendicular to said sensitive area and containing the center of the scanning field, means for selecting from the fluctuating signal output of the scanning head an odd harmonic component of the oscillation frequency, said odd harmonic component having the property of reversing its phase as the line moves from one side of said plane to the other, and means synchronized with the oscillations of said opaque means and recipient of said odd harmonic component for producing different electrical outputs for the two opposite phases.

12. The system as claimed in claim 11 comprising in addition means for selecting from the fluctuating output of the scanning head an even harmonic component of the oscillation frequency, and means in receipt of said even harmonic signal for producing another electrical output, whereby the absence of receipt of said even harmonic signal indicates the absence of a line within the scanning field.

13. A system for scanning a line comprising a scanning head, said scanning head comprising photosensitive means having a sensitive area positioned to have an image of the scanning field containing the line cast thereon, said photosensitive means adapted to cause fluctuations in an electric signal proportional to variations in light intensity, the length of the sensitive area in a direction transverse to the line being approximately equal to the width of the image of the line, opaque means disposed between the sensitive area and the line, means for oscillating said opaque means essentially transversely to the line for periodically obstructing the image of the line on the sensitive area, said opaque means oscillating with equal amplitude across a plane perpendicular to said sensitive area and containing the center of the scanning field, means for selecting from the fluctuating signal output of the scanning head an odd harmonic component of the oscillation frequency, said odd harmonic component having the property of reversing its phase as the line moves from one side of said plane to the other, and means synchronized with the oscillations of said opaque means and recipient of said odd harmonic component for producing different electrical outputs for the two opposite phases.

14. The system as claimed in claim 13 comprising in addition means for selecting from the fluctuating output of the scanning head an even harmonic component of the oscillation frequency, and means in receipt of said even harmonic signal for producing another electrical output whereby the receipt of said even harmonic signal indicates the absence of a line within the scanning field.

15. A head as claimed in claim 1 wherein said oscillating means comprises an arm having a right angle projection forming said opaque means at one end thereof, a U-shaped fold at the other end of said arm in the same plane as said right angle projection, said arm having a slot extending from the base of said U-shaped fold through a portion of each leg of said U-shaped fold, a flat spring received in said slot and forming an aperture with the base and legs of said U-shaped fold; a U-shaped

permanent magnet having its base received in said aperture, means for fastening said arm, flat spring and magnet rigidly together, an E-shaped electromagnet rigidly mounted with respect to said permanent magnet and magnetically coupled thereto, and means for rigidly fastening the ends of said flat spring.

16. The head as claimed in claim 15 wherein said last mentioned means comprises a tubular member having a pair of oppositely disposed slots at one end, said slots receiving the ends of said flat spring, said tubular member having a second pair of oppositely disposed slots at its one end immediately adjacent to said first pair of slots forming a pair of tongues therebetween, and wedge means within said second pair of slots to force said tongues tightly against the ends of the springs.

17. A vibrating assembly for use with a scanning head in a line tracing system comprising photoelectric means positioned to have an image of the line cast thereupon, and opaque means driven by said vibrating assembly for periodically obstructing the image of the line upon said photoelectric means; said vibrating means comprising an arm having a right angle projection forming said opaque means at one end thereof, a U-shaped fold at the other end of said arm in the same plane as said right angle projection, said arm having a slot extending from the base of said U-shaped fold through a portion of each leg of said U-shaped fold, a flat spring received in said slot forming an aperture with the base and legs of said U-shaped fold, a U-shaped permanent magnet having its base received in said aperture, means for fastening said arm, flat spring and magnet rigidly together, an E-shaped electromagnet rigidly mounted with respect to said permanent magnet and magnetically coupled thereto and means for rigidly fastening the ends of said flat spring.

18. The vibrating assembly as claimed in claim 17

wherein said last mentioned means comprises a tubular member having a pair of oppositely disposed slots at one end, said slots receiving the ends of said flat spring, said tubular member having a second pair of oppositely disposed slots at its one end immediately adjacent to said first pair of slots forming a pair of tongues therebetween and wedge means within said second pair of slots to force said tongues tightly against the ends of the springs.

19. The vibrating assembly as claimed in claim 18 comprising in addition a bar adjustably mounted across the other end of said tubular member and rigidly supporting said photoelectric means within operable proximity of said right angle projection.

20. A head for a system for scanning a line comprising photosensitive means having a sensitive area positioned to have an image of the scanning field containing the line cast thereon, the length of the sensitive area in a direction transverse to the line being equal to or greater than the width of the image of the line, continuous opaque means disposed between the sensitive area and the line, and means for oscillating said opaque means essentially transversely to the line for periodically obstructing the image of the line on the sensitive area.
